UNITED STATES PATENT OFFICE.

JOHN FRANKLIN HARRISON, OF TORONTO, ONTARIO, CANADA.

BAG HOLDER.

Application filed October 16, 1923. Serial No. 668,961.

To all whom it may concern:

Be it known that I, JOHN FRANKLIN HARRISON, a subject of the King of Great Britain, residing in the city of Toronto, county 5 of York, Province of Ontario, Canada, have invented certain new and useful Improvements in Bag Holders, of which the following is a specification.

My invention relates to improvements in 10 bag holders, such as those used to hang up cloth bags, and the objects of my invention are: First, to simplify the construction of holders of this class thereby enabling me to reduce cost of manufacture, and to 15 permit the holder to be associated with the bag very readily. Second, to construct a holder which will permit the bag to occupy the minimum amount of space, and yet be in a convenient position for use. Third, 20 to so form the coupling means for the ends of the holders as to relieve the same of all distorting strains, and thereby enabling me to further economize in cost of construction in that the holder can be made of lighter 25 gauge wire than any of those I am acquainted with. Fourth, to construct the coupling means for the ends of the holder which, while permitting the said ends to be uncoupled will prevent the accidental un- 30 coupling of said ends, and fifth, to provide a holder of the class set forth which will be flexibly held by its support so that in normal position, the front portion of the holder will rest against the back of the bag 35 and thus in effect close the mouth of the bag and so hide the contents thereof from view.

The construction of my holder will be 40 hereinafter more particularly described and what I claim as new will be set forth in the claim forming part of this specification.

Fig. 1 is a side elevation of my holder, 45 and Fig. 2 is an edge view thereof. Fig. 3 is a front view of portion of a cloth bag 50 associated with my holder, and Fig. 4 is a side elevation of a cloth bag showing my holder in dotted lines in different positions.

In the drawings, like characters of reference refer to the same parts. 55 I have particularly designed my holder to support a cloth bag adapted to temporarily house soiled clothing, and from close observation I have found that to-day economy in space is very essential and therefore

I have designed my bag holder so that when 55 not in use the same will occupy very little space, and at the same time the contents of the cloth bag will be hidden from view.

Several bag holders with which I am 60 acquainted are coupled permanently to the wall and consequently they project a considerable distance therebeyond even when 65 not in use, and therefore such bag holders not only occupy unnecessary space, but they also hold the mouth of the bag in such position that the contents thereof are readily 70 visible, and furthermore provide for the unobstructed entry of dust into the bag.

Although I have particularly designed 75 my holder to be used to support a bag made of cloth or any other suitable flexible material, particularly for indoor use, I find that the holder can be used to support a bag used in picking small fruit and vegetables. The holder may readily be strapped to the 80 waist, and because of the normal position of this holder, in effect the mouth of the bag is closed, and consequently in case the fruit picker should stumble, there is not as much likelihood of fruit spilling out of the bag 85 as would be the case were the holder permanently held in an open position.

The normal position of the holder will 90 permit the fruit picker, for example, to pass through shrubbery with the minimum obstruction offered by said holder.

Although I have shown the holder flattened, or more or less rectangular in form, the shape, broadly speaking, is immaterial.

The holder A is made of wire of the desired gauge, and at one end of this piece of wire is formed an eye B, which eye occupies substantially the same plane as the holder, as is clearly shown in Figs. 1 and 2. The other end of the piece of wire is 95 bent at an acute angle to the plane of the holder, as at I, and then further bent to form a hook C, which hook occupies the position more or less at right angle to the eye B. This bending of the wire at I is 100 done to permit the eye B to remain in the plane of the holder after the hook C is coupled therewith. Now in order to couple the said ends together, the holder must be flexed, and this flexing must occur when the 105 said ends are uncoupled.

The end D of the hook C is preferably longer than the diameter of the opening

through the eye B, and consequently the end D will come in contact with the side of the eye B and so prevent accidental uncoupling.

5 The bag E is provided in any usual way with a hem F, and an opening G to permit the holder to be threaded through said hem and the ends of the holder coupled together.

10 The normal positions of the holder A and bag are shown in full lines in Fig. 4, when the eye B is mounted on a nail or other support H driven into the wall or door. In this position, the weight of the holder moves the mouth of the bag into the position 15 shown in Fig. 4 and in effect closes the mouth and so hides the contents of the bag from view.

10 In order to place articles in the bag, the bag and its holder are moved into the dotted 20 position shown in Fig. 4 and during such movement obviously the holder A, together with the major portion of the hem F describe a vertically-disposed arc around the support or fulcrum H substantially at right 25 angles to the surface of the wall or other support for the fulcrum, and when the said holder is released by the hand, the same will travel under the influence of gravity through the same path, back to normal position.

30 The eye B obviously will be positioned midway the length of the holder A, so when the holder and its associated bag are supported on the nail H, the weight of the article will be substantially equally distributed 35 on each side of the holder.

40 Sufficient has been set forth to show that no distorting strain will be exerted against the eye B, since the said eye permits the holder A to be moved freely within a considerable angle using the pin or nail H as a fulcrum.

45 While I prefer to make the end D of the hook C longer than the diameter of the opening through the eye B, it must be

understood that I do not confine myself to this construction.

From my knowledge of the prior art, the bag holders are permanently held by fixed supports to project beyond the wall, and consequently they not only occupy unnecessary room, but such holders are liable to be damaged by individuals coming into contact therewith, thus necessitating outlay for upkeep. The normal position of my holder is such that no damage can be done thereto as outlined above. In other words, while the holders in the prior art are liable to distortion through weight carried by the bag and through exterior blows thereagainst, my holder is entirely free of damage from such causes.

50 While I have described and illustrated my preferred form of construction, this is merely for the purpose of illustrating a 55 holder having the movement before-mentioned.

What I claim is:

50 In a device of the type described, the combination with a bag holder comprising a 70 body portion formed from a single piece of wire bent into a form to correspond with the open mouth of a bag and having an eye formed by one end of said wire which is entirely positioned within the same plane 75 as that occupied by the said body portion, the other end of said wire being formed into a hook for being coupled with or uncoupled from said eye with the said hook occupying an angular position in respect 80 to said eye and having its end made longer than the diameter of the opening of said eye, of an element adapted to engage said eye for supporting said body portion in such a manner that the latter will normally depend, due to the force of gravity, from 85 said element and will be permitted to be swung into a substantially horizontally extending position.

JOHN FRANKLIN HARRISON.
